CUSHION CONSTRUCTION

Everett Mudge, Detroit, Mich.

Application October 5, 1937, Serial No. 167,357

7 Claims. (Cl. 155—179)

My invention relates to a new and useful improvement in a cushion construction adapted for use on seats, seat backs, upholstered arms and the like, in which a yieldable or cushion upholstered body is provided.

It is an object of the present invention to provide a cushion construction which will be simple in structure, economical of manufacture, durable, easily and quickly assembled, and highly efficient in use.

In the construction of many types of cushions which are spring supported, it is customary to cover the spring assembly with a padded body. Experience has shown that these padded bodies often lump, that is the filler of the pad gathers in separated lumps which results in uncomfortable-ness to the user and in a shortening of the life of the cushion construction.

It is an object of the invention to provide a cushion construction in which the lumping and undesirable features resulting therefrom will be avoided.

Another object of the invention is the provision of a cushion assembly which will retain its shape and be possessed of a comparatively long life.

Another object of the invention is the provision of a cushion construction which will be comfortably yieldable and yet which may be very easily and quickly adapted to a change of supporting springs so that varying degrees of flexibility may be obtained.

Another object of the invention is the provision of a pad which will engage the springs and which will be so constructed and arranged as to provide a maximum amount of movement while at the same time retain the springs in their operative relation.

Another object of the invention is the provision of a flexible pad or mat having reenforcing means embedded therein for resisting the thrusts de-livered thereto by the supporting springs.

Another object of the invention is the provision in a spring construction of a spring engaging pad so reenforced and constructed as to retain its shape under ordinary conditions of use.

Another object of the invention is the provision of a pad-forming member having a plurality of pockets faced outwardly from the under surface adapted for engaging and retaining the upper ends of the supporting springs in position.

Other objects will appear hereinafter.

The invention consists in the combination and arrangement of parts hereinafter described and claimed.

The invention will be best understood by a reference to the accompanying drawing which forms a part of this specification, and in which,

Fig. 1 is a fragmentary, front elevation view of the invention with parts broken away and parts shown in section.

Fig. 2 is a sectional view of the invention taken on line 2—2 of Fig. 1.

Fig. 3 is a bottom plan view of the invention.

Fig. 4 is a fragmentary, perspective view of the invention.

Fig. 5 is a fragmentary prospective view of a reinforcing frame used in the invention.

In the drawing I have illustrated the invention used with a spring assembly having a supporting frame 12 which is usually constructed of wood or other similar material for the reception of tacks and the like. Secured to this frame 12 is a spring assembly frame 13 which is usually formed as a closed rectangular frame. Connecting the opposite sides 14 and 15 of this spring assembly frame 13 are the cross bars 16 which are formed U-shaped in cross section and which are arranged in pairs facing inwardly of each other. The lower ends of the coiled supporting springs 17 are engaged in the channels of the cross bars 16 and these cross bars are then crimped to retain the springs in fixed position thereon.

The invention consists in the pad or spring en-gaging plate 18 which is preferably formed from sponge rubber. It may, however, be made from other kinds of rubber or from any suitable flexible material. Projecting downwardly from the lower surface 19 of the pad 18, are sleeves 20, these sleeves being arranged in spaced relation and located to conform to the location of the supporting springs 17. These sleeves 20, in conjunction with the pad 18, provide cups or pockets for the recep-tion of the upper ends of the coiled supporting springs 17. These cups or pockets are made of sufficient size to snugly receive the upper ends of the supporting springs and serve as a means for connecting these ends.

Depending from the pad 18 around its edges is an apron 21 which is of greater width than the length of the sleeves 20 so that the lower edge of the apron 21 is positioned between the ends of the cup-forming sleeves 20. Formed in the under surface of the pad 18 in the juncture of the apron 21, therewith, on opposite sides, is a groove 22. This groove is an endless groove and the end por-tions 22' are formed in the under surface of the pad 18 inwardly from the apron. A connecting arcuate groove 23 is formed in the inner face of the pad 18 outwardly of the end portions 22', this arcuate groove 23 communicating at its ends 50 with the end portions 22'. Positioned in the groove 22 and the end portions 22' is an endless wire 24 of sufficient rigidity to resist normal pres-sures which might be exerted upon the pad 18 tending to draw it from its original shape. A wire 25 is positioned in the arcuate groove 23 and connected either by clips, spot welding or in any other suitable manner at its ends to the wire 24 so that the end portions of the wire 24 are reenforced. Thus, I have mounted inwardly of the under sur- 60

face of the pad 18, a wire frame extending around this pad and reenforced at its opposite end portions.

5 Embedded in the pad 18 so as to lie just inwardly of the bottom of the grooves 22 and 23, is a screen 26. This screen, while permitting a certain amount of flexibility in the pad 18, still serves as a means for reenforcing the same and adding rigidity to it. This screen also serves to 10 strengthen the pad 18 and prevent a tearing or wearing of the same through the thrusts delivered thereto by the upper ends of the coiled springs 17.

15 When mounted in position, the reenforcing rods 27 which are connected at one of their ends to the spring assembly frame 13, are connected at their upper ends to the wire frame 25 at opposite sides thereof. Transversely extending grooves 28 are formed in the undersurface of the 20 pad 18 to permit the connection of the upper ends of the rods 27 to the wire 24. These grooves 28 as shown also extend slightly into the inner face of the apron 21. These reenforcing rods form braces to prevent relative displacement of the pad 25 18 and the spring assembly frame 13. Thus, they function to provide a rigid comparatively fixed structure, so far as lateral displacement is concerned, while at the same time they permit the approach and withdrawal of the pad 18 relatively 30 to the spring assembly frame 13 as well as the flexing of the pad 18 which usually takes place under normal conditions of use. An upholstering covering 29 is stretched over the entire assembly and tacked to the supporting frame 12 so that all 35 of the parts are enclosed and retained in their relative operative position.

When the pad 18 is flexed relatively to the plane of the spring assembly frame 13, the sleeve-forming cups will serve to retain the upper ends 40 of the coiled springs in position and due to the fact that padding has been eliminated above the supporting springs 17, a rubbing of the padding material is avoided. Consequently, the cushion will retain its shape and be possessed of a greater 45 life while at the same time the user will be afforded the comfort resulting from a structure having these characteristics. Experience has shown that a durable structure is provided and that a puncturing of the pad 11 by the coiled 50 springs is practically eliminated.

From the description given, it is believed obvious that the member 18, while preferably formed from sponge rubber or the like, may be formed from other materials which would permit the necessary flexibility and bending. The apron serves 55 as an engagement body for the upholstering cover 29 which is drawn downwardly over the upper surface of the pad 18.

While I have illustrated and described the preferred form of construction, I do not wish to limit myself to the precise detail of structure shown but desire to avail myself of such variations and modifications as may come within the scope of the appended claims.

65 What I claim as new is:

1. In a cushion construction of the class described, a flexible pad-forming body; a plurality of spaced pockets on the under surface of said body; means embodied in said body for reenforcing the same, said body having an endless groove formed on its under surface embracing and non-communicating with said pockets; and a reenforcing frame engaging in said groove.

2. In a cushion construction of the class described, a flexible pad-forming body; a plurality

of spaced pockets on the under surface of said body; means embodied in said body for reenforcing the same, said body having an endless groove formed on its under surface embracing and non-communicating with said pockets; a reenforcing frame engaging in said groove; and means for reenforcing the ends of said reenforcing frame.

3. In a cushion construction of the class described, a flexible pad-forming body; a plurality of spaced pockets on the under surface of said body; means embodied in said body for reenforcing the same, said body having an endless groove formed on its under surface embracing and non-communicating with said pockets; a reenforcing frame engaging in said groove; and means for 10 reenforcing the ends of said reenforcing frame, said reenforcing means engaging in grooves formed in the undersurface of said flexible body.

4. In a cushion construction of the class described, a flexible pad-forming body having a depending apron projecting downwardly from the marginal edges thereof, the under surface of said body having an endless groove formed therein, the sides thereof lying against the inner surface of said apron and the ends thereof being positioned inwardly from the inner surface of said apron, and a second groove positioned between each of the ends of said endless groove and the apron; and a reenforcing structure lying in said groove.

5. In a cushion construction of the class described, a flexible pad-forming body having a depending apron projecting downwardly from the marginal edges thereof, the under surface of said body having an endless groove formed therein, the sides thereof lying against the inner surface of said apron and the ends thereof being positioned inwardly from the inner surface of said apron, and a second groove positioned between each of the ends of said endless groove and the apron; a reenforcing structure lying in said groove; and a plurality of spaced pocket-forming members on said body and opening downwardly from the bottom thereof.

6. In a cushion construction of the class described, a flexible pad-forming body having a depending apron projecting downwardly from the marginal edges thereof, the under surface of said body having an endless groove formed therein, the sides thereof lying against the inner surface of said apron and the ends thereof being positioned inwardly from the inner surface of said apron, and a second groove positioned between each of the ends of said endless groove and the apron; a reenforcing structure lying in said groove; a plurality of spaced pocket-forming members on said body and opening downwardly from the bottom thereof.

7. In a cushion construction of the class described, comprising a pad-forming member having an endless groove formed on its under surface adjacent its edges, the end portion of said groove communicating with a groove extending substantially parallel thereto; a reenforcing frame engaged in said grooves; a plurality of cups projecting outwardly from the under surface of said pad-forming member; a spring assembly frame; a plurality of springs secured at one of their ends to said frame in spaced relation to each other and projecting upwardly therefrom each of said 60 springs engaging at its upper end in one of said cups; and means for connecting the sides of said spring assembly frame to the oppositely disposed sides of said reenforcing frame.
